UNITED STATES PATENT OFFICE

JOHN E. RENFER, OF CLEVELAND, OHIO, ASSIGNOR TO THE CLEVELAND ROCK DRILL COMPANY, OF CLEVELAND, OHIO, A CORPORATION OF OHIO

PNEUMATIC TOOL

Application filed July 1, 1929. Serial No. 375,193.

This invention relates broadly to pneumatic tools of the percussive type and more specifically to an improved valvular mechanism therefor which is adapted to effectuate the reciprocative movement of the piston.

One of the objects of this invention is to construct a valve of the reciprocative sleeve type which is positive of action, capable of being readily actuated and economic of manufacture.

Another object of this invention is to provide a valvular mechanism for a rock drill, or similar tool, the various elements of which may be readily separated from the machine for purposes of renewal or repair without the arduous labor of grinding and lapping the elements cooperating with the substituted parts.

Another object of this invention is to provide a valvular mechanism in which the passageways for the compressed fluid are organized with respect to the reciprocating elements within the machine to preclude the air cushioning effect offered the piston during its power stroke.

Another object of the invention is to construct a light, portable appliance, durable of construction and free from protuberant obstructions.

Other objects, more or less ancillary to the foregoing, and the manner in which all the various objects are realized will appear in the following description, which, considered in conjunction with the accompanying drawings, sets forth the preferred embodiment of the invention.

In the drawings

Fig. 1 is a longitudinal sectional view of a rock drill embodying the present invention and illustrating the valvular organization of the drill and the mechanism for elevating the drill against the work.

Fig. 2 is an enlarged sectional view illustrating the drill actuating valve and the piston in its retracted position;

Fig. 3 is a similar enlarged view illustrating the actuating valve and the piston in its forwardly disposed position;

Fig. 4 is a transverse sectional view taken

on a plane indicated by the line 4-4 in Fig. 1;

Fig. 5 is a transverse sectional view taken on a plane indicated by the line 5-5 in Fig. 1; and

Fig. 6 is a transverse sectional view taken on a plane indicated by the line 6-6 in Fig. 1.

As will be apparent from an examination of Fig. 1 the drill comprises a cylinder 10 having a piston 11 reciprocatively mounted

therein and a cutting tool tappet 12 coordinated with the piston and the cutting tool in the manner customarily employed in tools of this type. The piston 11 is formed with a head portion 13 and a shank or stem 14, the central portion of which is slightly reduced in diameter adjacent the head to accommodate the function of the valvular mechanism as will hereinafter be more fully described.

Mounted within the bore of the cylinder 10 there is a valve chest 15 comprising a tubular body having a flanged head 16 and a cap 17 which is telescopically supported within the body and axially bored to accommodate and guide the stem 14 of the piston. Adjacent

the valve chest head 16 there is a housing member 18 in which a rotatable control valve 19 is retained, the valve being arranged to provide for the admission of compressed fluid

into the cylinder 10 and the drill elevating instrumentalities 20. The control valve housing is formed with a recessed portion adjacent the valve chest 15 which, in conjunction with the valve chest constitutes a compression chamber 21.

The valve chest is provided with an annular recess formed in its inner peripheral wall, which is in fluid communication with the compression chamber 21

through a plurality of ported canals 23 in the valve chest and intercommunicating ports 24 in the valve chest cap 17. The portion of the valve chest in which the cap 17 is piloted is counterbored to receive a slide valve

25. This valve comprises a tubular body having a flange 26 formed in its outer peripheral wall intermediate its ends. In the valve assembly the flange 26 is adapted to be seated upon the shoulder formed by the inner end of the pilot portion of the cap and a ledge

27 at the base of the counterbore in the valve

chest. Circumambient the ledge 27 there is an annular recess 28 the circumferential portions of which are correlated with the flange 26 to be overlapped and closed thereby. Communicating with the annular recess 28 and the cylinder bore there is a plurality of passageways 29 which are provided to effect the retracted position of the valve 25 consonant with the retraction of the piston. The cylinder 10 is provided with an exhaust port 30 which is disposed in relation to the zone of travel of the piston 11 to lie adjacent the inner face of the piston head at the extended position thereof. An inlet passage 36 is likewise provided in the cylinder, this passageway being formed in a ribular boss in the cylinder and extends from ports 31 and 32 in the valve chest and cap respectively to a point adjacent the outer face of the piston at the extended position thereof.

20 In operation let it be assumed that the control valve 19 is adjusted to the position illustrated in Fig. 1 and that the compressed fluid is being admitted into the compression chamber 21. Let it also be assumed that the piston 11 is disposed in its retracted position as illustrated in Fig. 2. In this event it will be seen that the compressive force of fluid acting upon the rearward faces of the piston and piston stem will cause the translation of the piston and effect a striking blow against the tappet 12. During this event, however, the stem of the piston will be withdrawn from the opening 33 in the valve chest cap thereby subjecting the shoulder 34 of the slide valve to the influence of the compressed fluid within the compression chamber.

30 The slide valve, as most clearly shown in Figs. 2 and 3, is bored to provide a liberal clearance relative to the periphery of the piston stem 14. Consequently a column of the compressed fluid will flow through this opening and acting upon the shoulder 34' will tend to restrain the forward movement of the valve within the bore of the valve chest. However, it will be noted that the shoulder 34 is constructed with an area greater than that of the shoulder 34', so the compressive effort of the fluid will overcome this resistance and drive the slide valve against the ledge or valve seat 27. As the piston stem moves to its extended position it will obstruct the annular vein 22 and check the flow of compressed fluid into the cylinder, the inertia however, of the piston will carry it forward to the position illustrated in Fig. 3 where the exhaust port 30 is uncovered to effect the escape of the compressed fluid from the cylinder. The air entrapped in the valve chest recess adjacent the shoulder 35 will be expelled during the forward translation of the valve through the ports 29 when it will flow into the cylinder and escape through the exhaust port 30.

40 When the slide valve 25 is moved in its

forwardly disposed position as in Fig. 3, the port 31 will be opened and thus communication between the source of compressed fluid and the forward portion of the cylinder will be established. Continuing the reciprocating event of the piston the compressed fluid now admitted into the portion of the cylinder adjacent the forward face of the piston will cause the retraction of the piston and the closure of the exhaust port 30. When the stem of the piston closes the opening 33 in the valve chest cap and opens the annular recess 22 compressed fluid will be admitted to the portion of the cylinder adjacent the inner face of the piston. The combined entrapped atmosphere and the compressed fluid in the inner portion of the cylinder bore during this event will flow through the ports 29 and against the shoulder 35 of the slide valve and will thus cause the translation of the valve 25, the air entrapped in the valve chest recess adjacent the shoulder formed by the inner end of the cap 17 being expelled to atmosphere through suitable vent ports in the usual manner. The slide valve in assuming this retracted position closes the port 31 thus allocating the valvular members in the position first described and illustrated in Figure 2.

50 Although the foregoing description is necessarily of a detailed character in order to completely set forth this invention it is to be understood that the specific terminology is not intended to be restrictive or confining and it is further understood that various arrangements of parts and modifications of structural detail may be resorted to without departing from the scope or spirit of the invention as herein claimed.

I claim:

1. In a fluid actuated tool, a cylinder, a piston reciprocable therein, means on said piston to direct motive fluid to one end of said cylinder, a slide valve to control the admission of motive fluid to the other end of said cylinder, differential pressure areas on said valve arranged to be exposed to the pressure of the live motive fluid, and another pressure area on said valve constantly exposed to the pressure in said one end of said cylinder.
2. In a fluid actuated tool, a cylinder, a valve chamber associated therewith, a piston reciprocable in said cylinder and having a stem slidable in said valve chamber, a source of motive fluid, passages communicating therewith and with the opposed ends of said cylinder, said stem being arranged to close said passages, a slide valve in said valve chamber arranged to close the passage to one end of said cylinder to prevent the flow of motive fluid thereto, and means responsive to pressure changes in the other end of said cylinder to open said valve.
3. In a fluid actuated tool, a cylinder, a

valve chamber associated therewith, a piston reciprocable in said cylinder, a source of motive fluid, passages communicating therewith and with the opposed ends of said cylinder, means to control the admission of fluid to said cylinder including a valve in said valve chamber arranged to close the passage to one end of said cylinder and to be urged toward open position by the pressure of incoming motive fluid in said passage, and means responsive to pressures in the other end of said cylinder to hold said valve in closed position during the maintenance of a pre-determined pressure in said other end.

15 4. In a fluid actuated tool, a cylinder and a piston reciprocable therein, a passage for directing motive fluid to one end of the cylinder, a valve for controlling the flow of fluid through said passage comprising a valve seat carried by the cylinder and a valve member carried by the piston, passages directing motive fluid to the other end of the cylinder, a second valve for controlling the flow of fluid through the last mentioned passage, the second valve being actuated by incoming motive fluid and controlled by the flow of motive fluid through the first mentioned valve.

20 5. In a fluid actuated tool, a cylinder, a valve chamber associated therewith, a piston reciprocable in said cylinder and having a stem slidable in said valve chamber, motive fluid passages leading to the opposite ends of said cylinder, said stem being arranged to close said passages, a sleeve valve

25 surrounding and spaced from said stem arranged to close the passage leading to one end of said cylinder, and urged toward open position by incoming motive fluid in said passage, and means to hold said sleeve valve

30 in closed position during the maintenance of a pre-determined pressure in the other end of said cylinder.

In testimony whereof I hereunto affix my signature this 5th day of June, 1929.

45 JOHN E. RENFER.
